Primary Examiner—James Gandy*Assistant Examiner*—Stacia Sinuik*Attorney, Agent, or Firm*—Litman, McMahon and Brown, L.L.C.**[57] CLAIM**

The ornamental design for a vehicle wheel front face, as shown and described.

DESCRIPTION

FIG. 1 is a front perspective view of a vehicle wheel front face showing my new design; and.

FIG. 2 is a front elevational view thereof.

The broken lines are for illustrative purposes only, and the subject matter depicted therein constitutes no part of the claimed design.
